CLAIM

The ornamental design for a battery, as shown and described.

DESCRIPTION

FIG. 1 is an exploded perspective view of a new design for a battery;

FIG. 2 is an exploded front view thereof;

FIG. 3 is an exploded rear view thereof;

FIG. 4 is an exploded left side view thereof;

FIG. 5 is an exploded right side view thereof;

FIG. 6 is a top view thereof; and,

FIG. 7 is a bottom view thereof.

The broken lines shown in the drawings depict environmental structure or portions of the article that form no part of the claimed design.
